UNITED STATES PATENT OFFICE.

THOMAS DAVIS AND WILLIAM W. TYLER, OF CLEVELAND, OHIO.

FEED-WATER HEATER.

SPECIFICATION forming part of Letters Patent No. 337,670, dated March 9, 1886.

Application filed October 16, 1885. Serial No. 180,049. (No model.)

To all whom it may concern:

Be it known that we, THOMAS DAVIS and WILLIAM W. TYLER, of Cleveland, in the county of Cuyahoga and State of Ohio, have 5 invented certain new and useful Improvements in Feed-Water Heaters and Purifiers; and we do hereby declare the following to be a full, clear, and exact description of the invention, such as will enable others skilled in 10 the art to which it pertains to make and use the same.

Our invention relates to improvements in combined feed-water heaters and purifiers; and it consists in certain features of construction, and in combination of parts hereinafter 15 described, and pointed out in the claims.

In the accompanying drawings, Figure 1 is an elevation of our improved heater and purifier. Fig. 2 is an elevation, in section, at right 20 angles to the view shown in Fig. 1. Fig. 3 is an enlarged section of the valve for discharging sediment.

A represents the shell of the heater, that is usually round in cross-section with a dome-shaped top, A', but the form is not essential, 25 and may be varied according to circumstances. The dome A' terminates above, preferably in a cylindrical drum, A''.

The dome and bottom A'' are usually secured 30 by bolts or studs so that they are detachable, by means of which access may be had to the inside of the heater, for cleaning, repairs, or other purposes. Inside the casing has ledges a, for supporting the screens B and the con- 35 caved bottom plate, C, of the heating-chamber.

Between the screens B is the filtering-chamber B', the latter being filled with any suitable filtering material. Access to this chamber 40 may be had by removing the man-hole plate b. Below the filtering-chamber is the sediment-chamber D, from which leads the discharge-pipe D', provided with the valve d.

On the plate C rests the plate C', the two 45 plates inclosing the heating-chamber c. The plate C' is preferably dome-shaped, as shown, and is considerably smaller than the dome A, leaving a suitable space between the outer and inner plates, as shown. The plate C' has a series of small perforations, c'.

E is a steam-pipe leading from the steam- 50 space of the boiler, and is provided with a stop-valve, e. This pipe passes through the

top of the dome A' and screws into the top of the plate C', so as to discharge into the heating-chamber c. A stuffing-box, e', is usually 55 employed to make a tight joint where the steam-pipe passes through the dome A'.

F is the induction feed-water pipe, and is provided in the usual manner with the check-valve f and stop-valve f'. This pipe is pref- 60 erably connected with the side of the dome A', and discharges on top of the plate C'.

G is a pipe connected with the central or depressed part of the plate C, and leads down through the filtering-chamber, as shown in 65 Fig. 2. The water introduced through the pipe F passes through the orifices c' and falls in a spray into the heating-chamber, where it comes in contact with live steam admitted 70 through the pipe E. The water is of course raised to a high temperature and passes down through the pipe G, and as the sediment-chamber becomes filled the water is forced up 75 through the filtering-chamber into the chamber G', from which it passes through the pipe g to the boiler.

H is a small winged water-wheel, that is set in position for the current of water passing down through the pipe G to strike the wings or buckets h, so as to slowly rotate the wheel. 80 The wheel is mounted on a spindle, h', that outside the heater has a crank, I, to the wrist of which crank is attached the pawl i. This pawl engages the notches of the ratchet-wheel J, so that every revolution of the water-wheel 85 moves the wheel J one or more notches, according to the throw of the crank I. The wheel J is mounted on a shaft, J', the latter being journaled in a suitable box, j. Suitable stuffing-boxes, e'', form tight joints where the 90 shaft h' passes out of the shell A. The valve d of the pipe D' is closed in its elevated position, and is held closed by the pressure of water in the pipe. The valve-rod d' extends upward through the valve-casing, and is in 95 position to be engaged by the lug or cam K, the latter being attached to the ratchet-wheel, and by means of which engagement once during each revolution of the ratchet-wheel the valve is depressed or opened, and is held open 100 a short time until the cam draws off of the valve-stem, when the water again closes the valve. The heating and downward discharge of the water tend to precipitate the sediment

and deposit the latter on the plate A³, from which it is easily blown out if it is not neglected and allowed to remain too long, in which latter case the sediment forms a hard 5 crust that is removed with difficulty.

By means of the automatic mechanism hereinbefore described, every few hours, and before the sediment has had time to harden, it is blown out.

10 The apparatus is automatic in all of its functions, and needs little or no attention, except to occasionally remove or cleanse the filtering material.

15 The advantages of feeding pure water to the boiler and having the water heated to such a high temperature as will prevent a contraction of the boiler when the water is introduced, are too well known and appreciated to require further mention here.

20 What we claim is—

1. In a feed-water heater and purifier, the combination, with a sediment-chamber provided with a discharge pipe and valve, of a water-wheel arranged so that the latter is actuated by the movement of the feed-water, said water-wheel having suitable connecting mechanism, substantially as indicated, whereby the said discharging valve is operated automatically, substantially as set forth.

25 2. In a feed-water heater and purifier, the combination, with a sediment-chamber, a discharging pipe and valve, and a water-pipe leading to said sediment-chamber, of a water-wheel so located as to receive the discharge of said 30 water-pipe and be rotated thereby, said water-wheel having suitable connecting mechanism,

preferably as shown, for operating automatically the said discharge-valve, the parts being arranged and operated substantially as described.

4c

3. In a feed-water heater and purifier, the combination, with a heating-chamber above, a sediment-chamber below, an intermediate filtering-chamber, and a pipe leading from the heating-chamber and discharging into the 45 sediment-chamber, of a water-wheel located in the sediment-chamber in position to be actuated by the current of the feed-water, said water-wheel having suitable mechanism connected thereto, arranged substantially as indicated, for operating the discharge-valve of the sediment-chamber, the parts being arranged and operated substantially as set forth.

50

4. In a feed-water heater and purifier, the combination, with a water-wheel located in the 55 sediment-chamber in position to receive and be actuated by the feed-water introduced to the sediment-chamber, of a spindle and crank connected with the water-wheel, and a pawl connected with the crank and engaging a ratchet-wheel, the latter having a cam or lug for engaging the stem of the discharge-valve, the parts being arranged substantially as set forth.

60

In testimony whereof we sign this specification, in the presence of two witnesses, this 13th day of October, 1885.

THOMAS DAVIS.
WILLIAM W. TYLER.
